UNITED STATES PATENT OFFICE.

LOUIS SEILER, OF BALTIMORE, MARYLAND.

BODY-SUSPENDED BAG OR CASE.

1,416,238.

Specification of Letters Patent. Patented May 16, 1922.

Application filed February 25, 1921. Serial No. 447,814.

To all whom it may concern:

Be it known that I, LOUIS SEILER, citizen of the United States, residing at Baltimore, in the county of Baltimore and State of Maryland, have invented certain new and useful Improvements in Body-Suspended Bags or Cases, of which the following is a specification.

The invention relates to improvements in 10 a body suspended bag or case.

It is an object of the invention to provide a bag of a compact formation which may be suspended from the body and is formed with a plurality of pockets of different sizes and 15 located at different places in the bag for carrying various articles and permitting access to be readily had to any of said pockets.

The invention more particularly comprises a bag wherein the layers of material from 20 which the bag is formed are arranged upon one another in a manner to provide in the bag a number of individual pockets, each having separate closures and accessible from different points of the bag.

25 In the accompanying drawings, Figure 1 represents a side elevation of the bag. Figure 2 is a section on the line 2—2 of Figure 1. Figure 3 is a section on the line 3—3 of Figure 1; and Figure 4 is a sectional view on line 4—4 of Figure 1.

Referring now more particularly to the drawings wherein like reference characters indicate corresponding parts, the numeral 1 designates a suspension belt or the like, having 35 a suitable buckle at one end and adapted to pass around the body of the user. Carried by this belt are supporting straps 2 ejecting therefrom and attached to the compartment bag 3.

40 This bag is preferably composed of a base or rear layer 4 extending the full length thereof and constructed of any suitable fabric, rubber, or the like. Attached to the upper end of the rear layer 4 is a strip of 45 fabric, the same being stitched along the lines 5 and 6, and receiving therebetween the suspending straps 2. The line of stitching 5 forms a hinge for the flap 7 of the strip, which flap is provided with fastening devices 8 for a purpose which will later appear.

There is also attached to the rear layer 4 a relatively long intermediate strip or layer 9 stitched thereto by a line of stitching 10 55 passing entirely around the bag, this strip 9 projecting substantially the full length of

the bag or up to the transverse row of stitching 5 which unites the strip to the bag. The strips of flexible material 4 and 9 provide therebetween an elongated pocket 60 adapted to receive bags or other large articles. Within this pocket there is stitched strips of flexible material 11 preferably of chamois, or the like, adapted to be closed by closures 12 and constituting jewelry pockets 65 for receiving valuable articles of the user. These pockets are relatively smaller and do not take up much of the room formed in the pocket 13 which is produced by the strips 4 and 9.

70 Another intermediate fold of flexible material 14 is likewise stitched by the stitching 10 to the rear fold 4, and the fold 9 of the bag, its strip 14 being somewhat shorter than the strip 9 and having its upper end 75 entirely disconnected therefrom to provide a pocket 15 adapted to be closed by the hook and eye connection 16. This pocket is useful for many purposes where it is desired to carry smaller articles and may be closed by 80 the hook and eye connection 16 hereinbefore described.

85 Mounted upon the strip 14 is an outer flap or strip 17, which constitutes a portion of the outer surface of the bag and is united to the other strips thereof by the stitching 16. This strip is relatively short in length and provides an outer pocket 18 of a comparatively small capacity receiving such articles which it is preferable to deposit within a 90 small bag of this character. The strip 17 is of course disconnected from its upper end of the other strips of the bag, but to provide a closure for the pocket 18 formed by this strip I attach to the upper portion of the bag a 95 fold of material 19, the same being secured along its upper end to the fold 9 by the lateral rows of stitchings 20 and 21, the cross stitchings 21, and the stitching 22 along the sides thereof providing a support for the 100 flap 19 to permit the lower end 22^a thereof to be raised and lowered to permit access to be had to the pockets 15 and 18. The lower end 22^a of this flap is provided with hooks and eyes 23 for closing the pockets to prevent accidental displacement of the contents thereof.

105 From the foregoing it will be appreciated that by a novel arrangement of the flaps of the bag I am enabled to provide in a bag 110 occupying little space a plurality of pockets particularly fashioned for the reception of

various articles which will be appropriately received by said pockets. It will also be appreciated that all the pockets are provided with closures so as to prevent the accidental displacement of the contents thereof and such closures are permanently united to the bag in an efficient manner. While I have defined the material from which the bag is composed as consisting of cloth, rubber or the like, other fabrics or flexible material may be used without departing from the invention.

Having thus described the invention, what I claim is:

15 A compartment bag comprising an elongated flexible base 4, of flexible flaps 9, 14 and 17, respectively stitched to the base one

upon the other, said flaps being of progressively decreasing length and unstitched along the upper ends thereof to form in the bag a 20 plurality of independent differently sized pockets 13, 15 and 18, a strip 11 secured to the base 4 at the upper end thereof and forming in the large pocket of the bag a small pocket at the upper end thereof, a flap 12 stitched 25 to the base for enclosing the open end of said small pocket, a flap 7 stitched to the base and forming a closure for the large pocket of the bag, and a closure 19 adapted to be stitched to the base for closing the 30 pockets formed by the flaps 14 and 17.

In testimony whereof I affix my signature.

LOUIS SEILER.
